UNITED STATES PATENT OFFICE.

JOSEPH R. SMITH, OF WATERBURY, CONNECTICUT.

DESIGN FOR A GLOVE-FASTENER CAP.

SPECIFICATION forming part of Design No. 20,463, dated January 6, 1891.

Application filed June 20, 1890. Serial No. 356,149. Term of patent 14 years.

To all whom it may concern:

Be it known that I, JOSEPH R. SMITH, of Waterbury, in the county of New Haven, State of Connecticut, have invented and produced a new and original Design for Glove-Fastener Caps, of which the following is a full, clear, and accurate description.

Figure 1 is a plan view of a fastener cap, showing my design; and Fig. 2 is a section on $\times x$, Fig. 1.

The leading feature of my design consists in a central circular boss convexly rounded and imperforate surrounded by a corrugated circular border inclining inward and downward from near the outer margin of the cap to the depressed outer edge of the boss.

a is the central circular boss convexly

rounded and imperforate, the outer edge of which is depressed considerably below the plane through the top of the edge of the cap. ²⁰ This boss a is surrounded by a circular border b , which slopes inward and downward from near the outer margin of the cap to the depressed outer edge of the boss.

I claim—

The design for a glove-fastener cap herein shown and described.

In witness whereof I have hereunto set my hand.

JOSEPH R. SMITH.
